UNITED STATES PATENT OFFICE.

CARL HORIX, OF CHICAGO, ILLINOIS.

DESIGN FOR A COMBINED PENHOLDER AND CALENDAR.

Application filed February 19, 1927. Serial No. 20,815. Term of patent 7 years.

To all whom it may concern:

Be it known that I, CARL HORIX, a citizen of the United States, residing at Chicago, in the county of Cook and State of Illinois, have invented a new, original, and ornamental Design for a Combined Penholder and Calendar, of which the following is a specification, reference being had to the accompanying drawing, forming a part thereof.

In the drawing:

Fig. 1 is a front elevation and Fig. 2 is a plan view of a combined penholder and calendar showing my new design.

I claim:

The ornamental design for a combined penholder and calendar, as shown.

Chicago, Illinois, February 17, 1927.

CARL HORIX.
